WASHING MACHINE

Joshua D. Evans, Berkeley, Calif.

Application March 23, 1931. Serial No. 524,693

2 Claims. (Cl. 68—18)

This invention aims to provide a device for washing clothes and other articles.

It is within the province of the disclosure to improve generally and to enhance the utility of 5 devices of that type to which the invention appertains.

With the above and other objects in view, which will appear as the description proceeds, the invention resides in the combination and 10 arrangement of parts and in the details of construction hereinafter described and claimed, it being understood that changes in the precise embodiment of the invention herein disclosed, may be made within the scope of what is claimed, 15 without departing from the spirit of the invention.

In the accompanying drawings:

Figure 1 is a longitudinal horizontal section of the washer, most parts appearing in top plan; 20 Figure 2 is a transverse section of the washer.

Figure 3 is a longitudinal sectional view of one of the valves which let the water out of the compartments of the washer.

The washer embodies a horizontal, cylindrical 25 tank 66, carried by supports 67. The tank 66 has a plurality of transverse partitions 68 dividing the tank into washing compartments 69. Into these washing compartments 69, pipes 70 discharge, the pipes opening through the upper portion of the 30 tank 66. The pipes 70 extend upwardly and backwardly, and are provided at their upper ends with funnels 71, which receive liquid from a mixer, not shown.

The tank 66 has a plurality of outwardly opening doors 72, there being one of these doors for 35 each of the washing compartments 69. Brackets 73 are secured to the doors 72 of the tank 66, and are secured to a shaft 74, extended lengthwise of the tank, and journaled for rotation in bearings 75 on the tank. Intermediate its ends, the shaft 74 carries an arm 76 the arm 76 projecting from the shaft 74 in a direction opposite to the the arms 73. A counterweight 77 is mounted 40 for sliding adjustment on the arm 76, to offset the weight of the doors 72. This weight 77 may be of any desired size. It is held adjustably on the arm 76 by a set screw 78 threaded into the counterweight.

On the partitions 68, and on the ends of the 50 tank 66, there are bearings 79 carrying glands 80. Axially aligned shafts 81 are journaled in the bearings 79 and in the glands 80. The inner ends of the shaft sections 81 are secured at 82 to the ends of rotatable, cylindrical cages 83, 55 there being one of the cages 83 in each of the

washing compartments 69. The cages 83 are supplied with hinged doors 84 held closed by any suitable means, such as latches 85. The cages 83 are of open work construction about their peripheries, and slats 85 may be employed 60 to make the cages of the open work construction above referred to.

Gear wheels 87 are secured to the outermost shaft sections 81, and mesh with pinions 88 on a shaft 89 extended longitudinal of the washing tank 66, the shaft being journaled in bearings 90 on the tank. The shaft 89 is supplied at one end with fast and loose pulleys 91, or with any other suitable means whereby rotation may be imparted to the shaft. 70

The tank 66 carries a plurality of depending outlet pipes 92, there being one of these outlet pipes for each of the washing compartments 69. To each of the outlet pipes 92 is secured a coupling 93 provided at its lower end with an 75 outstanding flange 94 having a recess 95 in which is mounted a valve seat 96. The valve seat 96 is held in the recess 95 by the oppositely projecting arms 97 of a downwardly extended U-shaped guide 98, the arms being held 80 on the flange 94 by securing elements 99.

An upwardly closing conical valve 100 cooperates with the seat 96, and is provided with a downwardly extended stem 101, an upper abutment nut 104 being threaded on the stem 101 85. A lower abutment nut 102 is threaded on the stem 101. A compression spring 103 surrounds the stem 101. The lower end of the spring 103 bears on the bottom of the guide 98, and the lower end of the valve stem 101 slides in the 90 bottom of the guide. The upper end of the spring 103 engages the abutment nut 102. The nuts 102 and 104 have rounded ends 105 which project toward each other.

A shaft 106 extends lengthwise of the machine and is mounted for rocking movement in bearings 107 on the supports 67. At one end, the shaft 106 has a handle 108. Arms 109 are secured at 110 to the shaft 106. The arms 109 have forks 111, straddling the stem 101 of the 100 valve 100, between the rounded ends 105 of the nuts 104 and 102.

The water, properly charged with bleaching fluid, soap, or the like, passes into the tank 66 of the washer, by way of the pipes 70, and the washing 105 compartments 69 are filled to the desired level, the outlet valves 100 of Figure 3 being held closed by the spring 103. The shaft 89 is rotated by the pulleys 91, and rotation is imparted to the shaft 81 by way of the pinions 88 and the gear 110

wheels 87. Assuming that the garments or other articles which are to be washed are in the cages 83, the garments are whirled about, within the cages, and in the water in the compartments 69, when the cages are rotated along with the shaft 81. When the washing has been carried on to the desired extent, the doors 84 of the cages 83 are opened, the doors 72 on the tank 66 being opened, the weight 77 of Figure 2 facilitating the opening of the doors 84. The garments then may be removed from the cages 83. When it is desired to drain the compartments 69, the shaft 106 is rocked by means of the handle 108. The arms 109 on the shaft 106 cooperate with the nuts 104 and 102 of Figure 3 to depress the valves 100, against the action of the springs 103, thereby opening the seats 96, and permitting the dirty water to run out of the compartments 69 through the pipes 92. When the handle 108 is released, the springs 103 close the valves 100. It will be observed, referring to Figure 1, that separate packages of clothes may be washed in the respective compartments 69, since separate compartments and separate cages 83 are provided. The machine, therefore, can wash fine white materials, and coarse dye-discharging materials at the same time, without danger that the finer materials will be contaminated by the soiled water from the coarse and more dirty materials.

Having thus described the invention, what is claimed is:

1. In a device of the class described, a washer comprising an elongated horizontal tank, compartments in the tank, the tank having a door-way for each compartment, the door-ways being

aligned longitudinally of the tank, a rotary cage in each compartment, means for connecting the cages for rotation as one piece, each cage having a door-way, doors for the door-ways of the cages and aligned longitudinally of the tank, means for rotating the cages, in fixed relation to each other, to bring the doors of the cages into registration with the respective door-ways of the tank at one time, so that the doors of all the cages may be opened, and for the further purpose of rotating the cages to carry on a washing operation, when the doors of the cages are closed, doors for the door-ways of the tank, and mechanism for opening all the doors of the tank at once, to permit all of the doors of the cages to be opened, said mechanism comprising a shaft extended longitudinally of the tank, means for mounting the shaft for rocking movement on the tank, and transverse arms on the shaft, the doors of the tank being fixed to the arms.

2. A device of the class described, constructed as set forth in claim 1, in combination with a rigid arm on the shaft, and projecting in an opposite direction to the arms which carry the doors of the tank, a counter weight offsetting the weight of the doors and slidably adjustable on the rigid arm, and means for holding the weight in adjusted positions longitudinally of the rigid arm, the shaft being located adjacent to the uppermost part of the tank, and the rigid arm slanting upwardly, to render the weight readily adjustable at the hand of a person standing on the opposite side of the tank from the weight.
